DENTURE PACKING

Earl S. Mills, Eugene, Oreg.

Application March 14, 1944, Serial No. 526,459

3 Claims. (Cl. 18—5.7)

1

This invention relates to new and useful improvements in denture packing and more particularly to an adjustable device for exerting packing pressure on dental flasks to the end that the same can be closed and secured preparatory to heat processing.

An important object of the invention is to provide a device of the character stated which will exert sufficient pressure on a denture containing flask to permit proper closing of the flask without breaking the invested model or investment.

Other important objects and advantages of the invention will become apparent to the reader of the following description.

In the drawings:

Figure 1 represents a fragmentary side elevational view with parts broken away and in section.

Figure 2 is a side elevational view of the machine.

Figure 3 is a horizontal section taken on the line 3—3 of Figure 1.

Figure 4 is a top plan view of the clamp.

Figure 5 is a fragmentary side elevational view of the connector.

Figure 6 is a side elevational view of the clamp with a portion broken away.

Referring to the drawings wherein like numerals designate like parts, it can be seen that numeral 5 denotes a two-part vertically disposed shell having an inverted U-shaped frame 6 secured at its upper portion by securing elements 7. This shell 5 may be secured by a bracket 8 and securing element 9 and by any other attaching means found suitable, to a bench or other support.

A pressure plate 10 is slidable in the frame 6, the ends being recessed to permit straddling of the side portions of the frame 6 as is apparent in Figures 1 and 2.

A slide member 11 is vertically slidable through the top of the frame 6 and through a fixed partition 12 in close spaced proximity to the top of the frame 6. The top of this slide member 11 has a knob 13 and interposed between this knob and the top of the frame 6 is a coiled compression spring 14. One side of the slide member 11 has ratchet teeth 15 with which a slidable detent 16 is engageable, this detent being slidably disposed through the upper portion of one side of the frame 6 where it is provided with a finger hook 17. This detent 16 has a spring 18 for holding the same against the teeth 15. The lower end of the slide member 11 is connected to an up-standing flange 19 on the pressure plate 10.

2

Numerical 20 generally refers to a clamp in which a denture flask 21 may be placed. This clamp 20 consists of a bottom U-shaped section 22 having its upstanding portions apertured to receive eyes 23 at the lower ends of eye-bolts 24 which are disposed upwardly through slots in the ends of a bridge plate 25. Wing nuts 26 are provided for the upper threaded ends of the eye-bolts 24.

It can be seen, that a flask 21 is first set upon the clamp section 22 after which the bolts 24 are disposed through the slots in the bridge plate 25 and the wing nuts 26 secured down upon this bridge member 25 for preliminarily holding the flask closed.

A slot 27 is provided in one side wall of the shell 5 and through this extends an elongated foot lever 28 fulcrumed as at 29 and having a hook formation 30 at its inner end. This hook formation is preferably bifurcated and straddles the lower T-structure 31 of a rod 32, the latter being threadably disposed into a cross pin 34 journaled in bars as at 34a on the bottom of a frame-like connector 33. This allows for adjustment of the rod to regulate the force of a spring 40, thus allowing for a variation of pressure on the flask 21. The coiled tension spring 35 extends from the bottom of the connector 33 to connect to an anchor on the inside of the shell 5, this for the purpose of drawing the connector downwardly. At the top of the shell 5 is a pressure plate 36, the end portions of which are recessed to straddle the side portions of the frame 6. The frame 20 with its held denture flask rests upon this pressure plate.

Numerical 37 denotes a rod secured by a nut or nuts 38 at its lower end to the frame connector 33 and said rod 37 extends to the pressure plate 36. Interposed between the connector 33 and the pressure plate 36 is the coiled compression spring 40. It will be observed that the lower portion of the rod 37 is slidable through an opening in the connector 33.

A shaft 41 is provided in the lower portion of the shell 5 and has a notched detent 42 capable of engaging the hook end 30 of the lever 28 to hold the same when depressed. A spring 43 is provided for urging the detent 42 against the hook end of the lever 28. At the outer end of the shaft 41 is a short arm 44 to which is connected the lower end of rod 45, said rods extending through a guide 46 and having a hand knob 47.

It can now be seen, that with the parts as shown in Figure 1, a flask placed in the clamp

20 may be set upon the pressure plate 36 and the plate 10 pushed down against the same by the slide member 11 and held in this position by the detent 16.

The lever 28 may now be forced downwardly by the operator's foot and to be held in depressed position by the detent 42. Depression of the lever 28 forces the connector 33 upwardly in opposition to the spring 35. Upward movement of the connector 33 compresses the spring 40 against the pressure plate 36 and thereby yieldingly clamps the clamp 20 between said plates 36 and 10.

When it is desired that pressure be released, a slight pressure on the lever 28 and actuation of the control rod 45 to displace the detent 42 will permit return of the parts to normal position.

While the foregoing specification sets forth the invention in specific terms, it is to be understood that numerous changes in the shape, size and materials may be resorted to without departing from the spirit and scope of the invention as claimed hereinafter.

Having described the invention, what is claimed as new is:

1. In a denture packing machine, a pair of vertically slidable upper and lower pressure plates, spaced apart to receive a denture flask therebetween, manipulative means to slide the upper

plate downwardly against the denture flask into different set locked positions, and treadle-operative self-locking means for exerting yielding pressure upwardly against the lower plate.

2. In a denture packing machine, a pair of upper and lower vertically slidable pressure plates, a denture flask holder interposed between said plates and yieldable under pressure against the same, manipulative means to move the upper plate downwardly into different set positions against said holder, and treadle-operative means for subsequently exerting yielding pressure upwardly against the lower plate.

3. In a denture packing machine, a pair of upper and lower vertically slidable pressure plates, a denture flask holder interposed between said plates and yieldable under pressure against the same, manipulative means to move the upper plate downwardly into different set positions against said holder, and treadle-operative means for subsequently exerting yielding pressure upwardly against the lower plate comprising a treadle-forming lever vertically swingable and having a short lever arm, a rod movable upwardly by said arm, a vertically slidable connector between said rod and lower plate, operative by said rod, and a coil spring interposed between said connector and lower plate.

EARL S. MILLS.
